UNITED STATES PATENT OFFICE.

AXEL G. GULBRANSEN, OF SYCAMORE, ILLINOIS.

MECHANICAL PIANO-PLAYER.

No. 874,762.

Specification of Letters Patent.

Patented Dec. 24, 1907.

Application filed February 19, 1906. Serial No. 301,964.

To all whom it may concern:

Be it known that I, AXEL G. GULBRANSEN, citizen of the United States, residing at Sycamore, in the county of Dekalb and State of Illinois, have invented a certain new and useful Improvement in Mechanical Piano-Players, of which the following is a full, clear, concise, and exact description, reference being had to the accompanying drawings, forming 10 a part of this specification.

My invention relates to mechanical music instruments and has for its particular object improved construction and arrangement of the pneumatic valve action therefor.

15 My invention is particularly adaptable to pneumatic valve actions placed at the interior of pianos or organs. In instruments of this kind, particularly pianos, it is very desirable that this valve action and apparatus 20 be as compact as possible and arranged in such position that the piano is entirely free for tuning or adjusting purposes, and it is also desirable that the primary pneumatics be connected as directly as possible with the 25 striking hammers of the piano, and also that these pneumatics with their valve actions be readily accessible and removable from the instrument for purposes of inspection, adjustment and repairs.

30 According to my invention each primary pneumatic and its valve controlling mechanism is in a unitary structure, each structure being individually removably secured to a main mounting board which forms the rear 35 wall of the main air chamber, this air chamber running lengthwise of the piano directly to the rear of the keys so that the entire pneumatic action is disposed below the front upper panel board of the piano, thus leaving 40 the upper part of the piano entirely free for adjustment and other purposes. The movable part of each pneumatic is also connected directly with the corresponding abstract stem or rod leading from the rear end of the 45 corresponding piano key to the hammer. The construction and arrangement of the valve mechanism is also improved by my invention and other arrangements introduced, which make all parts very accessible, thus 50 allowing quick adjustment or repairs, and the details of my invention will appear better by reference to the accompanying drawings, in which

55 Figure 1 is an end view of the air chamber frame with the pneumatic mechanism attached, one of the pneumatics and its valve

action and the corresponding upper part of the air chamber being shown in section, part of the inclosing piano frame and key mechanism being also shown. Fig. 2 is a front view 60 of a section of the action mechanism. Fig. 3 is a rear view of a section of the action mechanism showing the connection thereof with the key rods, and Fig. 4 is a top view of a section of the pneumatic mechanism, the 65 cover of one valve block being partly removed to illustrate the arrangement of the valve.

The air chamber *a* is rectangular and extends lengthwise along the front of the piano 70 directly below the ledge 1 and directly behind the wall 2 of the piano structure, and this chamber is formed by the rear wall 3, a top wall 4, a lower wall 5 and the front wall or cover 6, this cover being hinged at one end 75 and provided with locking means such as hooks 8 at the top, whereby upon removal of the piano frame part 2 the cover may be opened to reveal the interior of the air chamber.

To the rear wall 3 are secured the various 80 similar pneumatic mechanisms, each mechanism comprising a body wall or block 9 to which is hinged the movable part 10 of the bellows 11, a spring 12 being suitably arranged tending to distend this bellows. In the front end of the block 9 is a cylindrical chamber 13 having the annular shoulder 14, about the edge of which is glued the valve 90 diaphragm 15, which diaphragm divides this chamber into an upper section 16 and a lower section 17, the lower section communicating through a passageway or channel 18 extending through the block 9, which channel 95 communicates with another channel 19 extending through the rear wall 3 of the air chamber. Directly above the compartment 13 and mounted on the block 9 is the valve block 20 having a cylindrical compartment or chamber 21 communicating with the chamber 13 through the cylindrical opening 22 which is of smaller diameter than the compartment 21. This compartment 21 connects with the channel 23 which communicates through channel 24 with the bellows 100 11. Glued over the top of the valve block 20 is a piece of leather 25 having the opening 26 concentric with the chamber 21 but of less diameter. Within the chamber 21 the valve 27 plays and is mounted on the valve 110 stem 28 which is shown as consisting of an ordinary wood screw engaging through the

valve which is locked thereto by a leather washer 29, the lower end of the stem or screw engaging the leather washer 30 which is glued to the diaphragm 15. The chamber 5 16 above the diaphragm connects through channel 31 with the air chamber *a* and the opening 26 leads to the atmosphere.

The valve may be formed, as shown, consisting of the top plate 32, which may be of 10 wood or other rigid material, and of the lower half 33 of felt, and a layer of thin leather 34 may engage about the felt to be glued at its edge to the edge of the top disk 33. The valve thus formed may be guided 15 and restrained between the guide pins 35, as shown, or these pins may be omitted and the valve left to adjust itself into proper seating to close the outlet openings. Each of the channels 19 for the various pneumatic 20 mechanisms connects through a separate hose or other conductor with the tracker board in a well known manner, and the lower section 17 below the diaphragm also connects with the air chamber through a 25 limited passageway 36 which may be conveniently provided by gluing or fastening a disk 37 of celluloid or other material before the outlet of the channel 18, and this disk have a small pin hole opening of suitable size 30 to form the proper adjustment.

The air chamber *a* is connected with exhaust bellows in any manner and the same reduced pressure exists above and below the diaphragm, owing to the fact that both these 35 compartments are normally connected with the air chamber, the upper compartment being connected through the passageway 31 and the lower compartment through the channel 18 and opening 36. As the music 40 sheet travels over the tracker board air under atmospheric pressure is admitted to the corresponding channels and this air rushes through the corresponding channels 19 and 18 to the lower compartments 17, and as the 45 upper compartment 16 is still under reduced pressure the diaphragm with the valve stem and valve head is suddenly thrown upwardly to carry the valve head away from the opening 22 and to force it against the leather 25 50 to close the opening 26. The bellows is, therefore, closed from connection with the atmosphere and is instead connected through opening 22 with the compartment 16 connected with the air chamber *a* and the bellows 55 immediately becomes collapsed. As the opening in the tracker board again becomes closed the air under atmospheric pressure in the channels 18 and 19 and in the compartment 17 will be relieved of its pressure 60 owing to the opening 36 connecting the channel 18 with the air chamber and the air at both sides of the diaphragm again becomes of the normal reduced pressure and equalized. Owing to the smallness of the 65 opening 36 and to the rapidity of the inrush-

ing air under atmospheric pressure upon opening at the tracker board, most of this air is effective in throwing up the diaphragm and very little passes into the air chamber. The leather top of the valve block 20 performs various novel and very useful functions. In the first place it forms the top inclosing wall for the valve chamber and being thin takes up very little space. In the second place the edges about the opening 26 afford a seating for the valve head, and as the leather gives more or less when the valve head is thrust upwardly the valve action becomes cushioned and much more elastic than if this wall were of rigid material such as wood, and there is also no noise.

Another feature of my invention lies in the direct connection of the bellows part 10 with the abstract stems or rods 38 leading to the piano hammers, an abutment piece 39 being glued or secured to each of these stems to be directly engaged by the projection 40 extending from the bellows part 10. Owing to this direct connection there is very little chance for lost motion.

Figs. 3 and 4 show the compact and novel arrangement of the pneumatic mechanisms, each of these mechanisms, as before stated, comprising only the bellows parts and the valve block secured thereto, and these mechanisms are secured at their ends to the rear wall 3 of the air chamber by means of screws 41. As the rods 38 are usually equally spaced and in a straight line, the pneumatic mechanisms must be arranged correspondingly, and I therefore arrange them in three rows, as shown, each row being offset so that the planes of the projections 40 are equally spaced.

If any of the mechanisms become defective or need adjustment the front part 2 of the piano may easily be removed, whereupon the air chamber structure with the attached pneumatic mechanisms may be pulled forwardly and upon opening of the hinged cover 6 and withdrawal of the proper screws 41 the desired pneumatic mechanism can easily be removed without in any way destroying adjustments or working parts. The disks 37 and the openings therethrough may also be readily adjusted by merely opening the cover 6.

Although not herein shown, the music carrying rolls, the motor and the various conducting pipes may all be carried on the same supporting structure and upon removal of the front panels of the piano the entire pneumatic player mechanism may be withdrawn from the instrument.

I thus provide a very simplified and compact arrangement of the primary pneumatic mechanisms and a direct connection thereof with the striking hammers. Each of the primary mechanisms is a complete individual structure which can be bodily removed from

the supporting wall without in any way interfering with its operative parts. The primary pneumatic arrangement may also be used with equal advantage in so-called outside piano or organ players.

As changes may readily be made by those skilled in the art without departing from the spirit of my invention, I do not wish to be limited to the exact construction and arrangement herein shown, but

I claim as new and desire to secure by Letters Patent:

1. In a mechanically operated piano, the combination with the abstract rods of the piano, of a vertical flat main air chamber, a plurality of pneumatic mechanisms, each mechanism being a unitary structure and comprising a main mounting block, actuating bellows secured below the block and primary pneumatic valve mechanism mounted in the block, each unitary structure being secured to the rear wall of the main air chamber by means of screws inserted from the front through the rear wall of the main chamber whereby each structure may be readily and independently removed, said pneumatic mechanisms being arranged in vertical and horizontal rows and each having operative connection with an abstract rod of the piano.

2. In a mechanically operated piano, the combination with the abstract rods of the piano of a main air chamber having a rear wall and a front hinged wall, pneumatic mechanisms arranged in vertical and horizontal rows in front of the foot of the abstract rods of the piano, a mounting block for each pneumatic mechanism, primary valve mechanism disposed in and on said mounting block, actuating bellows supported below the block and having direct operative connection with one of the abstract rods, each unitary mechanism being secured from the rear wall of the main air chamber by means of screws inserted from the front through said wall upon opening of the hinged front wall of the chamber.

3. In a mechanically operated piano, the combination with a main air chamber having the rear vertical wall 3 and the hinged cover 6, a mounting block 9 extending from

and secured to the rear wall 3 by means of screws 41 passing through the wall 3, an actuating bellows 11 supported from the under side of the mounting block, an abstract rod 55 for the piano, an abutment on said abstract rod, an extension 40 from the bellows for engaging with said abutment, and primary controlling valve mechanism supported on the mounting block, said mounting block, valve mechanism and bellows forming a compact unitary structure readily removable from the supporting wall 3 upon withdrawal of screws 41.

4. In a mechanically operated piano, the combination of a vertical, flat, main air chamber extending across the piano, abstract rods at the rear of the piano, pneumatic mechanisms supported from the rear wall of the main air chamber, a mounting 70 block for each mechanism, actuating bellows supported below the mounting block and having direct connection with one of the abstract rods, valve mechanism for controlling the operation of the bellows, a valve 75 chamber for the valve mechanism a passageway leading from the valve chamber to the main air chamber, a disk within the main air chamber applied over the end of the passageway for each pneumatic mechanism, and a 80 pin hole through each disk communicating with the corresponding passageway.

5. In a mechanically operated piano, the combination with a single, flat, main air chamber extending across the piano at the 85 front thereof, abstract rods for the piano to the rear of the chamber, pneumatic mechanisms extending rearwardly from and removably secured to the rear wall of the main air chamber, each pneumatic mechanism being 90 in the form of a compact unitary structure and comprising a mounting block, valve mechanism and actuating bellows, each actuating bellows having direct connection with the corresponding abstract rod. 95

In witness whereof, I hereunto subscribe my name this 17th day of February A. D., 1906.

AXEL G. GULBRANSEN.
